To all whom it may concern:

Be it known that I, Isaac L. Ferris, a citizen
of the United States, residing at Bridgeport,
county of Fairfield, State of Connecticut, have
invented a new, original, and ornamental Design
for a Flashlight Switch, of which the following
is a specification, reference being had to the ac-
companying drawing, forming part thereof.

Fig. 1 is a plan view of a flashlight switch
showing my new design,

Fig. 2 is a side elevation thereof, and

Fig. 3 is a perspective view.

I claim:

The ornamental design for a flashlight switch,
substantially as shown.

ISAAC L. FERRIS.
